RAILWAY TRAFFIC CONTROLLING APPARATUS

Application filed November 28, 1928, Serial No. 322,421. Renewed November 6, 1930.

My invention relates to railway traffic controlling apparatus, and particularly to apparatus of the type comprising train carried governing means controlled by energy received from the trackway.

The apparatus covered by the present application is an improvement on the apparatus disclosed and claimed in a co-pending application by Lloyd V. Lewis filed on August 2, 1927, Serial No. 210165, for railway traffic controlling apparatus.

I will describe one form of apparatus embodying my invention, and will then point out the novel features thereof in claims.

15 The accompanying drawing is a diagrammatic view illustrating one form of apparatus embodying my invention.

Referring to the drawing, the reference characters 1 and 1^a designate the track rails of a stretch of railway track over which traffic moves in the direction indicated by the arrow. These rails are divided, by means of insulated joints 2, into a plurality of successive track sections, of which only one section, A—B, is shown complete in the drawing. Train controlling current is supplied to the rails of this section from a suitable source of energy such as an alternator M. The current supplied to the trackway by this alternator may be of a frequency of the order of the usual commercial alternating current, such for example, as 60 cycles or 100 cycles per second.

The supply of current to the track rails is controlled by a code transmitting device comprising a plurality of rotatable cams each designated by the reference character O with a suitable distinguishing exponent. The cams O are driven at a constant speed by a suitable motor J which is supplied with current from the alternator M. The cam O¹ is provided with a plurality of swells spaced about its periphery, which swells successively operate a contact 6 to periodically close the contact as the cam O¹ is rotated. In similar manner the cams O² and O³ are provided with different numbers of swells which control contacts 7 and 8, respectively. One terminal of the alternator M is constantly connected with rail 1 of section A—B,

and the other terminal of the alternator is connected with the rail 1^a through a current limiting impedance Z, and one of the contacts 6, 7, or 8, depending upon traffic conditions.

It is manifest that the alternating current supplied to the rails of the trackway by alternator M is periodically varied at the frequency of operation of the contact of the code transmitting device interposed between the alternator and the track rail 1^a. The code transmitting device may be constructed to cause such variations at any reasonable frequencies, but for purposes of illustration, I will assume that the cams O are rotating at 20 revolutions per minute, that cam O¹ has 4 swells, that cam O² has 6 swells, and that cam O³ has nine swells. The selection between the several contacts of the coding device in accordance with traffic conditions may be accomplished in any suitable manner such, for example, as by means of a home relay 3 and a distant relay 4. The circuits for controlling these two relays form no part of my present invention and are omitted from the drawing for the sake of simplicity. For present purposes, it is sufficient to state that home relay 3 is normally energized but is de-energized when a train occupies the section immediately to the right of point B. The distant relay 4 is also normally energized but is de-energized when a train occupies either the first or the second section immediately to the right of point B. When relays 3 and 4 are both energized, so that the front contacts of both these relays are closed, current from alternator M, which current I will assume to be of 100 cycles per second, is supplied to the track rails over contact 8 operated by cam O³. Under these conditions, the alternating current supplied to the trackway is periodically varied at a frequency of 180 cycles per minute. Current supplied to the trackway under these conditions, I will hereinafter term the "clear" code. When relay 3 is energized and relay 4 is de-energized, contact 7 controlled by cam O² is included in the trackway circuit, and under these conditions the trackway is supplied with 100 cycle current interrupted at a frequency of 120 cycles per minute; this current

I shall hereinafter term the "approach restricting" code. In similar manner, when relay 3 is de-energized, a circuit is completed from alternator M to the track rails through 5 contact 6 operated by cam O¹, and the trackway is then supplied with 100 cycle current interrupted at a frequency of 80 cycles per minute, which current I will call the "approach" code.

10 A train, indicated diagrammatically at V, is provided with a receiver designated in general by the reference character P. This receiver comprises two magnetizable cores 22 and 22^a, carried on the train in advance of the 15 forward axle, and located in inductive relation with the two track rails 1 and 1^a, respectively. Core 22 is provided with a winding 23, and core 22^a is provided with a similar winding 23^a, the windings 23 and 23^a being 20 connected in series in such manner that the voltages induced therein by alternating currents flowing in opposite directions in the track rails at any instant are additive. The windings 23 and 23^a are connected, through 25 an amplifier E, with the primary 16 of a transformer Y, the secondary 17 of which is connected directly with a polarized relay D, that is, a relay which is responsive to the polarity of the current supplied thereto. 30 The amplifier E is preferably of the vacuum tube type which delivers a unidirectional output current that varies in accordance with variations in the input current. With apparatus of the type described, when any code 35 is being supplied to the trackway, each increase in the 100 cycle current in the trackway induces in secondary 17 of relay Y a current impulse which energizes relay D in one direction, and each decrease of trackway current induces a current impulse in secondary 40 17 which energizes relay D in the opposite direction. As a result, relay D is operated alternately, first in one direction, and then in the other, at the frequency of the code 45 supplied to the trackway.

The relay D controls apparatus which is selectively responsive to the frequency of operation of the relay. In the present embodiment of my invention, this apparatus is constructed as follows:

Associated with relay D is a transformer T comprising a primary 19 and a secondary 20. Direct current is supplied to the primary 19 of transformer T from a suitable 45 source of energy such as a battery 28, and this current is periodically reversed at the frequency at which relay D operates. As shown in the drawing, when relay D is energized in one direction to close contact 18-18^a, current flows from battery 28 through the lower half of primary 19 in one direction, but when the relay D is energized in the opposite direction so that contact 18-18^b is closed, current flows from battery 28 through the upper half of primary 19 in the opposite direc-

tion. It follows that when relay D is periodically reversed, the current in primary 19 of the transformer T is periodically reversed at the frequency of the periodic variation in the trackway current. As a result of this, 70 there is induced in the secondary 20 a low frequency alternating electromotive force which is supplied to a plurality of circuits each designated by the reference character C with a distinguishing exponent, and each comprising a reactor 24 and a condenser 21, by means of which the several circuits are tuned, respectively, to the several code frequencies. For example, circuit C³ is tuned 75 to resonance at the frequency of the "clear" code or 180 cycles per minute. A relay R³ is connected across a portion of reactor 24 of circuit C³ through a rectifier h³. In similar manner, circuit C² is tuned to resonance at 80 120 cycles per minute and relay R² is connected across a portion of reactor 24 of this circuit through a rectifier h². Relay R¹ is connected, through rectifier h¹ and reactor 27, directly with secondary 20 of transformer T, and relay R¹ is arranged to be energized when 85 relay D is receiving any of the train control code frequencies.

Associated with the relays R are a plurality of stick relays each designated by the reference character S with a distinguishing exponent. The relays R and S may control governing means of any suitable type, which, as here shown, is winding 55 of a magnet valve G arranged when energized to connect a reservoir 29 with a suitable source of fluid pressure not shown in the drawing. The reservoir 29 is connected with a relay valve H so that when this reservoir is charged valve H occupies the position shown in the drawing and a pneumatic relay 31 is connected by 100 pipe 128 with a source of fluid pressure so that contact 32 of this relay is closed. Pipe 128 controls also a "brake application valve" 105 (not shown) for causing an application of the brakes when this pipe is connected to atmosphere. When winding 55 of valve G becomes de-energized, the reservoir 29 is connected with atmosphere through a restricted orifice 34 and also through a whistle 33 which gives an audible indication to the engineer.

After a brief interval of time, such, for example, as 6 seconds, the pressure in reservoir 29 is so reduced that piston 30 of valve H reverses, thereby venting pipe 128 to atmosphere and applying the brakes. At the same time the reversal of valve H connects the pneumatic relay 31 with atmosphere, opening contact 32. If magnet valve G is again energized, reservoir 29 is again charged with fluid pressure so that valve H is restored to its original position and pneumatic relay 31 closes its contact 32.

The train is also provided with a manually operable acknowledging switch a located at some convenient place within the reach of the 120 125 130

engineman, and comprising a normally closed contact 52 and a normally open contact 71. When the acknowledging switch is operated, contact 52 is opened, and contact 71 is closed. Furthermore, a reset switch, designated by the reference character r , and comprising a normally closed contact 53 and a normally open contact 106, is provided, and located outside the cab where it will be inaccessible to the engineman when the train is in motion.

In explaining the operation of the apparatus as a whole, I will first assume that the "clear" code is being supplied to the trackway so that the trackway current is being interrupted at the frequency of 180 cycles per minute. Relay D therefore operates at the rate of 180 cycles per minute and alternating current of a corresponding frequency is supplied by secondary 20 of transformer T.

Relays R^1 and R^3 are therefore energized, but relay R^2 is de-energized because the circuit C^2 is not resonant at the frequency of the current now supplied to such circuit. With relay R^3 energized, current flows from battery 28, through wires 37 and 38, front contact 39 of relay R^3 , wire 40, lamp 41, wire 45, front contact 46 of relay R^3 , and wires 47 and 48, back to battery 28. The lamp 41 is therefore lighted to indicate "clear". The circuit just traced is provided with a branch which passes from wire 40, through wires 49 and 14, winding 35 of relay S^3 , and wires 15 and 58 back to wire 45. It is therefore plain that winding 35 of relay S^3 is connected in parallel with lamp 41, and that relay S^3 is energized. Under these conditions a circuit is closed for valve G, passing from battery 28, through wires 37 and 89, front contact 50 of relay S^3 , wire 51, contact 52 of acknowledging switch a , contact 53 of the reset switch r , wire 54, winding 55 of magnet valve G, wire 56, front contact 57 of relay S^3 , and wires 90 and 48 back to battery 28. Valve G is therefore energized, so that the brakes are not applied.

I will next assume that a change occurs in traffic conditions so that the "approach restricting" code is supplied to the trackway. Relay R^3 therefore opens and relay R^2 picks up, relay R^1 remaining in its energized condition. The circuit for lamp 41 is now open at front contacts 39 and 46 of relay R^3 so that this lamp is extinguished. Winding 35 of relay S^3 is also de-energized, and a circuit is closed for winding 36 of this relay from battery 28, through wires 37 and 38, back contact 39 of relay R^3 , wires 59 and 60, front contact 61 of relay R^2 , wires 62 and 86, front contact 87 of relay S^3 , wire 88, winding 36 of relay S^3 , wires 85, 76, and 66, back contact 46 of relay R^1 , and wires 47 and 48, back to battery 28. The parts are so constructed that the current supplied to the circuit just traced opposes the effect of the current supplied to winding 35 as described above. The net effect, therefore, is to rapidly neutralize the field of winding 35 and force the relay S^3 to its open position. Of course, as soon as contact 87 of relay S^3 opens, winding 36 is de-energized, so the relay does not again pick up, but remains in its de-energized condition. The circuit for magnet valve G is opened when front contacts 50 and 57 of relay S^3 open, so that the valve starts the reduction of pressure in reservoir 29, and causes whistle 33 to sound.

Since relay R^2 is now energized, current flows from battery 28, through wires 37 and 38, back contact 39 of relay R^3 , wires 59 and 60, front contact 61 of relay R^2 , wire 62, lamp 42, wire 63, front contact 64 of relay R^2 , wires 65 and 66, back contact 46 of relay R^3 and wires 47 and 48 back to battery 28. The lamp 42 is therefore lighted to indicate "approach restricting" and, by the change of visual indication, to inform the engineman that upon the expiration of the time interval required for the blow-down of reservoir 29, an automatic application of the brakes will result. If, however, prior to the reversal of valve H the engineman operates the acknowledging switch a , he may forestall an automatic application of the brakes in the following manner:

When contact 71 of switch a is closed, current flows from battery 28, over wires 37 and 38, back contact 39 of relay R^3 , wires 59, 67, 68, and 69, contact 32 of pneumatic relay 31, wire 70, contact 71 of acknowledging switch a , wires 72, 73 and 74, winding of relay S^1 , wires 75, 81, 76, and 66, back contact 46 of relay R^3 and wires 47 and 48, back to battery 28. Relay S^1 therefore becomes energized and closes a pick-up circuit for relay S^2 from battery 28, over wires 37 and 38, back contact 39 of relay R^3 , wires 59, 67, and 77, front contact 78 of relay S^1 , wire 79, winding 35 of relay S^2 , wires 80, 81, 76, and 66, back contact 46 of relay R^3 , and wires 47 and 48 back to battery 28. Relay S^2 therefore picks up.

The closing of front contact 82 of relay S^2 completes a pick-up circuit for relay S^3 , from battery 28 over wires 37 and 38, back contact 39 of relay R^3 , wires 59, 67, and 58, front contact 82 of relay S^2 , wires 83 and 88, winding 36 of relay S^3 , wires 85, 76, and 66, back contact 46 of relay R^3 , and wires 47 and 48 back to battery 28. The relay S^3 therefore closes its front contacts. When front contact 87 of relay S^3 becomes closed, a stick circuit is closed for this relay from battery 28, over wires 37 and 38, back contact 39 of relay R^3 , wires 59 and 60, front contact 61 of relay R^2 , wires 62 and 86, front contact 87 of relay S^3 , wire 88, winding 36 of relay S^3 , wires 85, 76, and 66, back contact 46 of relay R^3 , and wires 47 and 48, back to battery 28. The acknowledging switch a may now be restored to its

original position, thereby closing contact 52 and opening contact 71. The circuit for relay S¹ is therefore opened and this relay becomes de-energized, and the opening of contact 78 thereon de-energizes relay S², but relay S³ maintains its front contacts closed by virtue of the stick circuit just traced and including winding 36 of this relay. With relay S³ energized and contact 52 of switch a closed, valve G is energized over the circuit previously traced for this valve through front contacts 50 and 57 of relay S³. It follows therefore that when the train is receiving the "approach restricting" code, and if the engineer has acknowledged the change in traffic conditions from "clear" to "approach restricting" the relay S³ will be held energized and the magnet valve G will be energized to prevent an automatic application of the brakes.

Under some conditions, it may happen that when the train is receiving the clear code, relay R³ will become de-energized for a brief interval under circumstances which should not require a brake application. For example, as the train passes from one track section to the next track section, the supply of train controlling current to the receiver P may be interrupted for a brief time. Of course, the brakes will not be applied until the expiration of the time required to operate valve H, but as soon as valve G becomes de-energized the whistle 33 will commence to operate, and it is desirable to have this happen only when it is necessary to acknowledge a change in traffic conditions. With apparatus involving my invention, therefore, I delay the de-energization of valve G, following the opening of relay R³. Thus if relay R³ becomes de-energized, the circuit for winding 35 of relay S³ is opened. But valve G is not de-energized until relay S³ opens, and if relay R² does not pick up to close the circuit for winding 36, the relay S³ is somewhat slow releasing. It will therefore be plain that the whistle 33 does not sound until relays R³ and S³ have opened in succession, and the parts are proportioned so that the release times of these two relays bridge the ordinary time interval during which relay R³ might be accidentally de-energized.

It should be pointed out that after operation of the acknowledging switch a to close contact 71, the acknowledging switch must be again restored to its original position to close contact 52 after relay S³ has been picked up, in order to permit the magnet valve G to become energized.

Furthermore, if the acknowledging switch a is not operated before valve H reverses, the operation of the acknowledging switch will be ineffective to prevent an automatic application of the brakes. The reason for this is that as soon as valve H reverses, the pneumatic relay 31 operates to open contact 32,

but the contact 32 is included in the pick-up circuit for relay S¹ so that after this contact is open, manipulation of the acknowledging switch a cannot pick up relay S¹. If valve H does reverse, the train must be brought to a full stop in order to enable the engineer to operate the reset switch r before valve H can be restored. When switch r is operated, a branch is closed from wire 69, through wire 105, contact 106 of reset switch r and wire 107 back to wire 73. It will be plain that the closing of contact 106 shunts current around the contact 32 of pneumatic relay 31 and around contact 71 of the acknowledging switch a. When the rest switch r is operated, therefore, the relays S¹, S², and S³ are picked up in order in exactly the same manner as has already been explained for the operation of these relays upon manipulation of acknowledging switch a. When relay S³ has become energized, the reset switch r may be restored to its original position, thereby allowing relays S¹ and S² to drop. Relay S³ remains energized and magnet valve G becomes energized in the manner already described.

I will next assume that upon a further change in traffic conditions, the "approach" code is supplied to the trackway. Relay R² opens, but relay R¹ is still energized by the current of 80 cycles per minute which is now supplied to it by transformer T. The de-energization of relay R² interrupts the circuit for lamp 42 and also breaks the stick circuit for relay S³. The relay S³ therefore becomes de-energized, and opens the circuit for magnet valve G. The whistle 33 is therefore operated and the blow down of reservoir 29 is initiated so that an automatic application of the brakes will result at the expiration of a time interval unless the engineer acknowledges. The necessity for this acknowledgment is indicated by the extinguishment of lamp 42 and also by the lighting of lamp 43, which latter lamp is now energized by current which flows from battery 28 over wires 37 and 38, back contact 39 of relay R², wires 59 and 60, back contact 61 of relay R², wire 91, front contact 92 of relay R¹, wire 93, lamp 43, wire 94, front contact 95 of relay R¹, wire 96, back contact 64 of relay R², wires 65 and 66, back contact 46 of relay R³, and wires 47 and 48 back to battery 28.

If the engineer wishes to forestall an automatic application of the brakes, he operates the acknowledging switch a before valve H reverses. Since relay R³ is de-energized, the closing of the contact 71 completes the circuit for relay S¹ and this relay picks up, and in turn closes the circuit for winding 35 of relay S². Furthermore, the closing of contact 82 of relay S² picks up relay S³. Acknowledging switch a can now be restored to its original position. When this happens, 130

the opening of contact 71 opens the circuit for relay S^1 and this relay becomes de-energized. Relay S^2 , however, is held in its energized position by current which flows from battery 28 over the circuit already traced for lamp 43 as far as wire 93, and thence over wire 97, front contact 98 of relay S^2 , wire 99, winding 36 of relay S^2 , wires 81, 76, and 66, back contact 46 of relay R^3 and wires 47 and 48 back to battery 28. Relay S^2 is therefore held closed as long as the "approach" code is received on board the train. With contact 82 of relay S^2 closed, relay S^3 is also energized and since contact 52 is closed, the magnet valve G is also energized over front contacts 50 and 57 of relay S^3 , to prevent an automatic application of the brakes. It should be pointed out that should the pneumatic relay 31 open its contact before the engineman actuates the acknowledging switch a , the acknowledgment will be ineffective and he must bring his train to a full stop and operate the reset switch r to pick up the stick relays S.

I will next assume that the track circuit current is cut off to give the most restrictive indication of the system. This indication is designated as "caution slow speed". Relay D does not periodically reverse and relays R^3 , R^2 , and R^1 are therefore all de-energized, lamp 43 becomes extinguished, and the stick circuit for relay S^2 is opened. Relay S^2 therefore becomes de-energized, and the opening of front contact 42 thereon de-energizes relay S^3 . The magnet valve G is therefore de-energized to commence the blow down of reservoir 29 and to sound the whistle 33. The de-energization of relay R^1 also lights lamp 44, current flowing from battery 28, over wires 37 and 38, back contact 39 of relay R^3 , wires 59 and 60, back contact 61 of relay R^2 , wire 91, back contact 92 of relay R^1 , wire 100, lamp 44, wire 101, back contact 95 of relay R^1 , wire 96, back contact 64 of relay R^2 , wires 65 and 66, back contact 46 of relay R^3 and wires 47 and 48 back to battery 28. If the engineman wishes to acknowledge the change in traffic conditions to prevent an automatic application of the brakes, he operates the acknowledging switch a . The relays S^1 , S^2 , and S^3 are therefore picked up in sequence. The engineman then restores the acknowledging switch to its original position. Relay S^1 is now maintained in its energized condition by current which flows over the circuit for lamp 44 as far as wire 100, and thence through wire 102, front contact 103 of relay S^1 , wires 104 and 74, winding of relay S^1 , wires 75, 81, 76, and 66, back contact 46 of relay R^3 and wires 47 and 48 back to battery 28. Relay S^1 therefore remains in its energized condition and since contact 78 of this relay is closed, relay S^2 is also picked up, and relay S^3 is energized over front contact 82 of relay S^2 . The magnet

valve G is therefore energized by current from battery 28 over the circuit including front contacts 57 and 58 of relay S^3 .

Should traffic conditions now change in such manner that the "approach" code is supplied to the trackway, relay R^1 becomes energized, but relays R^2 and R^3 remain de-energized. The energization of relay R^1 completes the circuit for lamp 43 and extinguishes lamp 44 and opens the stick circuit for relay S^1 . Relay S^1 therefore becomes de-energized but the stick circuit for relay S^2 is now closed at front contact 92 of relay R^1 and front contact 98 of relay S^2 . The de-energization of relay S^1 therefore does not affect relays S^2 or S^3 and does not de-energize magnet valve G. Upon a change in traffic conditions from the "caution slow speed" to the "approach" therefore, no acknowledgment is necessary upon the part of the engineman to prevent an automatic application of the brakes.

If, now, traffic conditions change from "approach" to the "approach restricting" condition, relay R^2 becomes energized. The energization of relay R^2 extinguishes lamp 43 and lights lamp 42 and breaks the stick circuit for relay S^2 at back contact 61 of relay R^2 . The stick relay S^2 therefore opens, but the stick circuit for relay S^3 is now closed at front contact 61 of relay R^2 and front contact 87 of relay S^3 . The relay S^3 therefore holds its front contacts closed and magnet valve G continues to receive current from battery 28 so that no application of the brakes results from a change in traffic conditions from "approach" to "approach restricting".

Finally, if the "clear" condition is reestablished, relay R^3 becomes energized and relay R^2 opens. Lamp 42 is therefore extinguished and lamp 41 is lighted. The stick circuit for relay S^3 is also broken so that winding 36 of relay S^3 becomes de-energized. But a circuit is now closed for winding 35 of relay S^3 over front contacts 39 and 46 of relay R^3 as described hereinbefore. It will be remembered, however, that windings 35 and 36 are connected in opposition, so that when winding 35 becomes energized, the field of winding 36 is first neutralized to de-energize the relay, which then again picks up under the influence of the current in winding 35. During a short interval of time, however, relay R^3 is energized, and relay S^3 is open, and during this interval, current flows from battery 28, through wires 37 and 38, front contact 39 of relay R^3 , wires 40 and 49, back contact 50 of relay S^3 , wire 51, contact 52 of switch a , contact 53 of switch r , wire 54, winding 55 of valve G, wire 56, back contact 57 of relay S^3 , wires 58 and 45, front contact 46 of relay R^3 , and wires 47 and 48 back to battery 28. Valve G is therefore held energized while relay S^3 is open, and after relay S^3 again picks

up, valve G is energized over the circuit first traced for this valve including front contacts 50 and 57 of relay S³. It follows that no application of the brakes results from a change from "approach restricting" to "clear" traffic conditions.

In conclusion, it should be pointed out that the apparatus is arranged in such manner that upon any change in traffic conditions from a less restrictive to a more restrictive indication, an automatic application of the brakes will result unless the engineman operates the acknowledging switch *a* during the time interval required for the blow down of reservoir 29. Upon any change from a more restrictive to a less restrictive indication however, the magnet valve G does not become de-energized and no acknowledgment by the engineman is necessary.

Furthermore, the apparatus is arranged to sound the whistle 33 to warn the engineman of a change in traffic conditions which necessitates his acknowledgement, but the whistle does not operate if relay R³ is de-energized for a brief interval of time while the train is proceeding under "clear" conditions.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a train carried differential relay having two opposed windings, means located partly in the trackway for energizing one winding of said relay under certain traffic conditions, means operating upon a change to certain other traffic conditions to energize the second winding to open said relay, means under the control of the engineman and effective under said other traffic conditions to energize said second winding to close the relay, a signal arranged to be operated when said relay is open, and governing means on the train set into operation at the expiration of a fixed interval of time after said relay is opened.

2. Railway traffic controlling apparatus comprising a first and a second train carried relays, means for selectively energizing said relays in accordance with traffic conditions, a third relay having two opposed windings, a circuit for one winding of said third relay including a front contact of said first relay, a pick-up circuit for the other winding of said third relay under the control of the engineman and including a back contact of said first relay, a stick circuit for said other winding of the third relay including a front contact of said third relay and a front contact of said

second relay as well as a back contact of said first relay, a valve controlled by said third relay, and train governing means controlled by said valve.

3. Railway traffic controlling apparatus comprising a first and a second train carried relays, means for selectively energizing said relays in accordance with traffic conditions, a third relay having two opposed windings, a circuit for one winding of said third relay including a front contact of said first relay, a pick-up circuit for the other winding of said third relay under the control of the engineman and including a back contact of said first relay, a stick circuit for said other winding of the third relay including a front contact of said third relay and a front contact of said second relay as well as a back contact of said first relay, a magnet, a first circuit for said magnet including a front contact of said third relay, a second circuit for said magnet including a back contact of said third relay and a front contact of said first relay and train governing means controlled by said magnet.

4. Railway traffic controlling apparatus comprising a first and a second train carried relays, means for selectively energizing said relays in accordance with traffic conditions, a third relay having two opposed windings, a circuit for one winding of said third relay including a front contact of said first relay, a pick-up circuit for the other winding of said third relay under the control of the engineman and including a back contact of said first relay, a stick circuit for said other winding of the third relay including a front contact of said third relay and a front contact of said second relay as well as a back contact of said first relay, a magnet, a first circuit for said magnet including a front contact of said third relay, a second circuit for said magnet including a back contact of said third relay and a front contact of said first relay, a signal arranged to operate when said magnet is de-energized, and means effective upon the expiration of a time interval after said magnet becomes de-energized to apply the brakes.

In testimony whereof I affix my signature.
